Patented Dec. 26, 1961

191,995

SWIMMER'S DEPTH GAUGE

Le Roy O. Brown, Chicago, Ill., assignor to Colorado Oil and Gas Corporation, Denver, Colo., a corporation of Delaware

Filed Aug. 8, 1960, Ser. No. 61,661

Term of patent 14 years

(Cl. D52—6)

FIG. 1 is a perspective view of a swimmer's depth gauge showing my new design;

FIG. 2 is a side view thereof;

FIG. 3 is a bottom view thereof; and

FIG. 4 is an end view thereof.

The strap is shown broken away to indicate indeterminate length.

I claim:

The ornamental design for a swimmer's gauge, substantially as shown and described.
